UNITED STATES PATENT OFFICE.

LESTER L. PRAHAR, OF NEW YORK, N. Y.

DESIGN FOR A BELT-BUCKLE.

SPECIFICATION forming part of Design No. 36,486, dated August 11, 1903.

Application filed July 7, 1903. Serial No. 164,609. Term of patent 7 years.

To all whom it may concern:

Be it known that I, LESTER L. PRAHAR, a citizen of the United States, and a resident of the city of New York, borough of Brooklyn, in the county of Kings and State of New York, have invented a new, original, and ornamental Design for Belt-Buckles, reference being had to the accompanying drawing, in which is shown a side elevation of a buckle embodying my new design.

I claim as new and desire to secure by Letters Patent—

The ornamental design for a belt-buckle, as shown.

In testimony whereof I have signed my name to this specification in the presence of two subscribing witnesses.

LESTER L. PRAHAR.
